UNITED STATES PATENT OFFICE.

MAX SANDT, OF BIELEFELD, GERMANY, ASSIGNOR TO FIRM BIELEFELDER MASCHINENFABRIK VORMALS DURKOPP & CO., BIELEFELD, OF BIELEFELD, GERMANY.

FEED-ACTUATING MECHANISM FOR SEWING-MACHINES.

1,118,059.

Specification of Letters Patent.

Patented Nov. 24, 1914.

Application filed October 19, 1912. Serial No. 726,708.

To all whom it may concern:

Be it known that I, MAX SANDT, a citizen of the Empire of Germany, residing at Kaiserstrasse 165, Bielefeld, Germany, have 5 invented certain new and useful Improvements in Feed-Actuating Mechanism for Sewing-Machines; and I do hereby declare the following to be a full, clear, and exact description of the invention, such as will 10 enable others skilled in the art to which it appertains to make and use the same.

For the setting or adjusting devices for the feed mechanism of sewing machines as hitherto constructed lever mechanisms of 15 many different descriptions have been employed located in the casing of the machine and actuated from the shaft in connection with the arm.

According to the present invention the 20 whole of these intermediate parts are dispensed with: all the parts for controlling the variations in length of the stitch being located in the simplest manner upon and around the shaft in connection with the 25 arm.

The invention is illustrated on the accompanying drawing in which:—

Figure 1 is a vertical section taken at right angles to the shaft in connection with 30 the arm; Fig. 2 is a view partly in section in the longitudinal direction of the shaft in connection with the arm.

b is an eccentric mounted on the shaft a in connection with the arm. This eccentric 35 works in a sliding block c. The block c in turn works in a guideway e¹ with parallel sides formed in the head d of the actuating rod. At the other side the head of the actuating rod is formed with a cylindrical 40 boss e which in turn works in a guideway e¹ with parallel sides formed in a part f located in the casing of the machine and centrally disposed with respect to the shaft a. Attached to the part f provided with 45 the guideway e¹ is a setting handle g by means of which it is possible to fix the part f in the desired position.

The operation is as follows:—Beneath the 50 plate of the sewing machine are located, in a known manner, the pushing or rocking spindles for transmitting the movements to the feed. The actuating rod d¹ operates one of these spindles. As soon as the eccentric b on the shaft in connection with 55 the arm is set in motion, it communicates

a backward and forward movement to the actuating rod d¹ and the head d of the guide rod, while the sliding block c moves up and down in the guideway with parallel sides located in the head of the actuating 60 rod.

If the part f provided with the guideway e¹ is so set that the plane e² passing through its middle line is perpendicular to the plane d² passing through the axis of the actuating rod d¹ it is obvious that no movement is communicated to the transmission shafts or spindles located at the lower part of the machine casing all that is produced is a rocking movement around the point where 70 the actuating rod d¹ is jointed to the feed rollers. If now the part f with its parallel guideway e¹ is moved by means of the setting screw g so as to bring the middle line e² of the path into some angular position 75 which is greater or smaller than 90°, the result is that in addition to the swinging motion of the boss-like projection e on the head d of the actuating rod, the inclination of the guideway e¹ causes the actuating rod 80 d¹ and the head thereof to have an up and down movement depending upon the angle.

The smaller the angle becomes starting from 90° the greater is the upward and downward movement of the actuating rod 85 d¹ and the greater the movement transmitted to the feed mechanism, that is to say the length of the stitch depends upon the angle. If the adjusting screw g is set above the neutral line, where no motion is 90 transmitted, the feed mechanism moves in the forward direction, but if the setting screw is turned through the neutral line and to some lower position a reversal of the direction of motion is the result and the 95 device moves backward.

What I claim and desire to secure by Letters Patent of the United States of America is:—

1. In a device of the type described the 100 combination of a casing, a shaft rotatably mounted in said casing a guide way centrally and rotatably mounted on said shaft, a feed actuating rod having an opening in the head thereof larger than said shaft and 105 through which said shaft extends, a boss on one side of said head adapted to coact with said guideway, an eccentric secured to the shaft, a guideway formed on the opposite side of said head in which said eccentric 110

operates and means for adjusting the inclination of said first mentioned guideway.

2. In a device of the class set forth the combination of a shaft, an eccentric mounted on said shaft, an actuating rod for the feed provided with a head formed on one side with a guideway for said eccentric and on the other side with a circular boss, located substantially concentrically with respect to the shaft, a second guideway in connection with the casing for the reception of the

aforesaid boss and mounted loosely around the said shaft, and means for adjusting the inclination of said second guideway as and for the purpose set forth.

In testimony whereof, I affix my signature, in presence of two witnesses.

MAX SANDT.
